REFRIGERATING APPARATUS

Application filed February 13, 1930, Serial No. 428,052. Renewed February 18, 1933.

The invention disclosed in this application relates to refrigerating apparatus of the absorption type.

In absorption refrigerating apparatus it is essential that certain parts be cooled in order to produce the proper operation. Such parts are usually the rectifier, the condenser, and the gas return loop, where such a device is utilized. Impounded and running water have been utilized heretofore for this purpose. Such a cooling medium presents a number of disadvantages by reason of the bulkiness of the apparatus, where impounded water is used, the necessity of keeping the tanks filled, and the wastefulness of running water. Furthermore, heretofore there has been a total loss of the heat of the condenser or, in other words, there has been no utilization of the heat of the condenser for promoting the driving off of the gas during the boiling operation from the loop or the boiler.

In the past there has been no efficient mode of controlling the operation of an absorption refrigerating plant when applied to a box or refrigerator to account for the various climatic changes without resorting to complicated mechanism in the gas circuit.

The present invention aims to over-come entirely the use of water or liquid cooling medium and employs an air cooling arrangement for the rectifier, the loop and the condenser, all arranged so that proper cooling effect is applied to these parts with the utilization of the heat of the condenser for assisting in the driving off of the gas during the heating operation and increasing the circulation in the generator. The cooling effect of the returning gas during the cooling period is also utilized to promote absorption in the loop and generator during the cooling period. The particular embodiment is one wherein the condenser is provided with fins in heat radiating relation with respect to heat radiating fins arranged upon the loop so that during the heating period the heat of the condenser is transmitted to the loop during the heating period and the cooling effect of the returning gas through the condenser is transmitted to the loop for increasing the absorption in the loop and generator during the cooling period.

In addition to the foregoing the entire apparatus has suitable flues arranged in the refrigerator structure so that the rectifier, on the one hand, will have its own draft of air

passing its radiating fins without being effected by the draft of air through another main flue arranged to produce a draft of air about the generator and through the condenser and loop cooling fins which are arranged below the generator and, therefore, not effected by the heat therefrom.

The invention also aims to provide a regulating means for controlling the cooling effect of the refrigerator by manipulating the draft through the main flue past the generator and condenser.

Other features of invention will be brought out in the following description, drawings and claims.

Referring to the drawings, Fig. 1 is a front view in perspective, showing the entire intermittent refrigerating apparatus removed from the refrigerator; Fig. 2 shows this apparatus applied to a refrigerator; Fig. 3 is a detail view of the damp control; Fig. 4 is a view of the back of the box; Fig. 5 is a top plan view of the storage; Fig. 6 is a section upon the line 6—6 of Fig. 5; Fig. 7 is a section upon the line 7—7 of Fig. 4.

In the drawings, 1 illustrates a refrigerator casing comprising a lower compartment 1, a refrigerating chamber 2, heat insulated on all sides, as at 3, 4, and 5. The insulations 5, at the top, has buried in it the storage, as will appear. The sides of the box are continued back to provide a rear vertical channel including three flues 6, 7, and 8. The flue 6 is a small flue for the gas supply and return between the condenser and storage, as will appear, while the flue 7 is for conducting away the heat of the apparatus during the heating period, and flue 8 is for providing a flue for separate air passage past the rectifier and promotes circulation in the flue 7 by its proximity thereto. The bottom of the box is open at 9 and within the chamber 1 there is a housing member or casing 10 provided with a door 11 and extending from the bottom front edge in broken diagonal arrangement back to the flue 7. This casing is interrupted at the back corner by the flue 8 which extends to the floor and is open at the bottom, as at 12. The casing 10 forms a generating chamber 10' for the generator and it is open at the bottom 9, as is obvious. The flue 7 at substantially the point corresponding to the bottom of the refrigerating chamber is provided with a damper 13 mounted upon a horizontal pivot rod 14 and normally held closed.

by a spring 15. Mounted below the refrigerating chamber is a suitable rod 16 having a handle 17 at the front, provided with a projection 18 adapted to engage in any of the 5 holes 19 provided in a holding plate 20, secured to the box. The rear end of this rod projects into the flue 7 and is there provided with a cam 21 adapted to be rotated into engagement with the damper to open the same 10 and hold it in any adjusted position. By means of this damper the draft in the generating compartment 10' of the chamber 1 and through the condensers may be regulated thereby regulating the speed of operation of 15 the entire apparatus and the cooling effect in the box.

The refrigerating apparatus is of the intermittent type with an oscillating gas circuit leading to the storage tank and evaporator. 20 It comprises a boiler 22 to be heated by a gas burner or other heating means, not shown. This boiler or generator is within the generating compartment 10' formed in the chamber 1 so that it is affected by the draft control by 25 the damper 13. Below this boiler or generator and in the extreme bottom of the box so as to be affected by cool air circulated therethrough is a main condenser comprising coils 23 having a multiplicity of the fins indicated at 24. In heat radiating contact with these fins are a gang of loop and condenser fins 25 which have passing through them a section of the main condenser comprising the coils 26 arranged near the bottom of these fins 25 and 30 adjacent the main condenser. These fins also have passing through them coils 27 forming the gas return loop connected as at 28 to a pipe 29 leading up at the center into the bottom of the boiler, as shown in Fig. 1. Both 35 outer ends of these coils are connected by curved pipes 30 and 31 to the outer ends of the loop coils 27. Suitable projections similar to the part marked 32 are provided on each of these pipes 30 and 31 to collect sediment. Extending upwardly from the top 40 of the boiler is a gas outlet pipe 33 passing to a point in the flue 7 near the top thereof and returning in a pipe 34 to a point near the bottom of a trap or seal 35 and below any 45 liquid collecting therein, as shown in Fig. 1. Extending from the top of this trap above the liquor therein is an up rectifier pipe 36 provided with a plurality of vertically disposed fins 37 extending substantially the full 50 length thereof to a point near the top of the box.

This pipe 36 communicates by a pipe or connection 38 with a down rectifier tube or element comprising an outer casing or tube 39 provided with fins 40 and an inner tube 41. The top of the annular space between these two tubes 39 and 41 is sealed with an annular sealing plate 42. At the lower end this annular space is sealed off as at 43, so 55 that the space between these tubes forms an

annular down channel for the gas in its course past this rectifier tube or element, cool air passing up past the fins 40 and through the inside of the tube 41. The extreme bottom or end of this annular rectifying element is connected with a pipe 44 leading up through the bottom of the trap 35 and to a point above the surface of the liquid therein, as shown in Fig. 1. It is obvious that any boiler liquor collecting in this down leg of the rectifier can pass up onto the upper surface of the liquor in the trap, a point which is important in this type of apparatus. Above the lower point of this annular element is a tube 45 leading down and connected to the top or inlet of the condenser tubes 26. The other end these condenser tubes is connected by a pipe 46 to the main bank of condenser tubes 23 is connected to the riser 47 which leads to the storage and the evaporator structure, as will appear. 75

Extending up into the trap 35 to a point below the mouth of the tube 44, as shown in Fig. 1, is a loop pipe 48 which extends down and terminates in two branches 49 and 50, the former being connected to a right hand pipe 31 as at the point 51 and the left hand at the point 52, the latter point being lower in the pipe 30 than the point of entrance of the pipe 51 in the pipe 31. The gas on the return from the evaporator, as will appear, enters the trap 35 above the liquor therein, passes down through this tube 48 to the opposite ends of the loop where it enters the two pipes 30 and 31 at different levels and creates a circulation in the loop and results in absorption in this loop and in the boiler. This arrangement is very effective for not only initiating absorption and the start of the cooling cycle but also promotes absorption. 105

The riser 47 extends to the top of the box and supplies liquified ammonia gas to the receiver and also conveys the expanded gas from storage to the trap 35 from whence it passes to the generator during the cooling 110 period.

The storage comprises, as shown in Fig. 5, a rectangular tubular tank 53 forming a closed circuit arranged horizontally and buried in the insulation 5 at the top of the 115 box. This rectifier has upon its top four domes 54, 55, 56 and 57. 55, 56 and 57 are substantially alike, and each is in communication with the storage by a suitable opening 58, as shown in Fig. 2. Within each of these domes is a baffle plate 59 provided with a plurality of openings 60 spaced from a lateral opening for receiving a pipe 61 leading to the dome 54. As shown in Fig. 5, there are three of these pipes 61 connecting three of the domes 55, 56 and 57, to the dome 54. All of these pipes enter, as shown in Fig. 6, below a diagonal baffle plate 62 provided with an opening 63 at a low point. Above this baffle is another baffle 64 extending di- 120

agonally in the opposite direction toward it but leaving a passage 65 past it. The center and top of this dome receives the riser 47. After the rectified ammonia gas passes to this storage, it enters the dome 54 and passes through the opening 63 and through openings 66 into the storage. This operation is continuous all during the heating period while the storage and the evaporator are being supplied with liquefied ammonia. When the heating period is terminated and evaporation starts there is considerable boiling and foaming in the storage and the effect of this foaming action is produced by reason of these four outlets to the riser 47 through which the gas returns to the still absorber. Without a device of this kind the foaming or boiling of the ammonia gas tends to cause quantities of unevaporated liquified ammonia to pass down through the pipe or riser 47.

Communicating with the bottom of the storage is the evaporator grid and it is formed of pipe bent back and forth in return bends 67, the outer ends both leading by pipes 68 and 69 to the bottom of the storage near the back of the box. At the front and center loop, or return bend, there is a center pipe leading to the back manifold 71 connected to the various return bends and communicating by side legs 72 and stem 73 with the bottom of the storage. This manifold pipe 71 is also connected to a suck back drain pipe 74 connected to a suitable trap 75 which also communicates by a short lateral pipe 76 with the pipe or riser 47. This trap is a type familiar to those skilled in the art and is arranged to support in the storage and evaporator the proper volume of liquid refrigerant, passing, from time to time, any boiler liquor which might find its way into the storage and evaporator.

Assuming that the still absorber contains a solution of water and ammonia gas under pressure and that heat is applied, the effect of the heat is to drive off the gas from the water and cause it to travel up the pipe 33 down the pipe 34 to the trap 35 and to a point below liquor therein. The loop thus formed by the pipe parts 33 and 34 provides a liquid seal preventing the return of gas to the boiler through this path. For instance any gas returning to the trap will depress the liquor therein and force a column thereof up into the pipe 34, this column causing the gas to return to the boiler through another course, as will appear. The gas passing from the pipe 34 below the liquor bubbles up therethrough and passes up through the up pipe or leg 36 where it is cooled by the fins 37 and by the draft of cool air passing up through the flue 8. The gas passing from the top of the tube 36 passes over into the annular rectifying down element or leg where it is cooled by the fins 40 and thence passes by the

pipe 45 to the coils 26 of the condenser. Any liquid collecting in the annular rectifier element will pass through the pipe 44 to the upper surface of the liquid in the trap where it will again have a tendency to gasify, due to the heat of the trap and the liquor therein, and pass back into the system, leaving any boiler liquor in the trap. Undue collection of boiler liquor in this trap will pass out through the pipe 48 to the loop and thence to the boiler. The hot gas flowing through the pipe 45 has its heat dissipated by the fins 25 which are air cooled by circulation of air up through the bottom of the refrigerator into the chamber 10' and up through the main flue 7, the heat of the generator and of the condenser promoting the circulation of cool air through these fins. However, the heat transmitted to the fins 25 by the condenser coils 26 is transmitted to the loop coils 27 and thence to the liquor therein which results in ammonia gas being driven from the liquor in these coils and also tending to heat the liquor in the boiler by producing circulation therein. The gas finds its way through these coils 26 through the pipe 46 to the back of condenser coils 23 which are finned, as stated, and are cooled to the point of liquifying the gas in them. From time to time this liquid gas, collecting in these coils, is driven up through the pipe 47 to the storage and thence to the evaporator grid. It collects until the heating period is terminated.

When the heating period is terminated, the heat of the generator and the condensers, etc. continue a rapid circulation of cooled air up through the condensers. Thus cooling the lower bank and also the upper bank and through the fins of these parts reduces the temperature of the loop, which now being a region of lower pressure attracts the gas in the storage and evaporator. This action is transmitted through the pipe 48 to the trap 35. It is also transmitted to the pipe 33 and the pipe 34. This latter pipe is below the level of the liquor in the trap 35 and liquid seal is produced in the pipe 34 and the suction effect is transmitted through the pipe 44, the annular rectifier, pipe 45, the condenser pipe 47, the storage and the evaporator. In this way the returning gas must pass to the loop coils 27 and in so doing is converted into bubbles in the end pipes of the loop where it elongates against the upper curved surface of the end pipes and becomes absorbed in the boiler liquor, there being a circulation set up by the returning gas in the boiler and loop producing rapid absorption of the gas and refrigerating in the refrigerator. The degree of refrigeration may readily be controlled by the damper 13 in the main flue 7, since this damper regulates the amount of cool air passing the condenser and the generator.

What I claim is:

1. In absorption refrigerating apparatus, a still absorber, an evaporator and a condenser and loop structure all connected in operative cycle, said condenser and loop structure comprising condenser elements, loop elements, and heat transferring fins common to each other and to both said condenser and loop elements, whereby heat from said condenser elements is effective upon said loop elements during the heating period and the cooling effect of the gas on its return through the condenser during the cooling period is effective upon said loop.
- 15 2. Refrigerating apparatus as in claim 1 wherein the condenser elements include a main condenser portion, air cooling fins carried thereby, an auxiliary condenser portion having fins, and said loop element is arranged in the fins of said auxiliary condenser portion.
- 20 3. In absorption refrigerating apparatus, an evaporator, a flue housing, a still absorber arranged in said housing, a gas return loop connected to the bottom of the still absorber and arranged below the same and comprising a plurality of loop elements, a condenser below said loop, and heat radiating fins common to both said loop and condenser.
- 25 4. Refrigerating apparatus as in claim 3, wherein the condenser comprises a lower main portion and an upper auxiliary portion in heat transfer relation with said fins adjacent said loop, and suitable connections for establishing a closed operative cycle between said elements.
- 30 5. Refrigerating apparatus as in claim 3 wherein the loop is of back and forth coil form in several convolutions under the still absorber, a connection between substantially the physical center of said loop and the center of the still absorber, end connections between the ends of said loop and the bottom of the still absorber, and means for conveying the returning gas to both said end connections.
- 35 6. Refrigerating apparatus as in claim 3 wherein the loop is of back and forth coil form in several convolutions under the still absorber, a connection between substantially the physical center of said loop and the center of the still absorber, end connections between the ends of said loop and the still absorber, and gas return means connected to said end connections at different levels to promote starting of the cooling cycle and absorption.
- 40 7. In absorption refrigerating apparatus, a still absorber, a condenser, an evaporator, a liquid seal trap for establishing proper circuiting of the gas during the heating and cooling periods, and a rectifier in the form of a vertical loop having two legs, one entering the trap above the liquid therein, the other extending downward and connected to the condenser, and vertically arranged heat radiating fins carried by both of said legs.
- 45 8. In refrigerating apparatus as in claim 7 wherein the down leg of the rectifier is connected at its bottom by a tube to the trap above the liquid therein and by a pipe above its bottom to the condenser whereby any liquor thrown down in said down leg will be conveyed back to the trap and not to the condenser.
- 50 9. Refrigerating apparatus as in claim 7 wherein the down leg of the rectifier is in the form of a tubular annulus having an air opening up through the center, and fins on the outside.
- 55 10. Refrigerating apparatus as in claim 7 wherein the down leg of the rectifier is in the form of a tubular annulus having an air opening up through the center, and fins on the outside, a drain connected to the bottom of said tubular annulus and leading to the trap above the liquid therein, and a gas pipe also connected to said tubular annulus above the bottom and leading to the condenser.
- 60 11. In absorption refrigerating apparatus, a still absorber, a condenser, an evaporator, a liquid seal trap for establishing proper circuiting of the gas during the heating and cooling periods, a gas loop connected to the boiler and comprising an up leg and a down leg, extending into said trap below the bottom thereof and below the liquid therein, a rectifier loop having an up leg connected to the top of said trap, fins carried by said up leg, a down rectifier leg, fins carried thereby, a drain pipe connected to the bottom of said down leg and leading to the trap above the liquid therein, a condenser pipe connected to said down leg above the bottom thereof and leading to the top of the condenser.
- 65 12. In absorption refrigerating apparatus, a still absorber, and an evaporator comprising a storage above said still absorber, an evaporator grid in gravitating communication with said storage, and connections between said grid and said storage comprising end connections and a center connection.
- 70 13. In absorption refrigerating apparatus, a still absorber, a condenser, and an evaporator comprising a storage above said still absorber, an evaporator grid comprising a plurality of loops and connecting the ends of the grid to the storage and a center end connection also leading to said storage, connections between said grid and said storage comprising end connections and a center connection, said storage being in tubular form and in a closed horizontal circuit, a plurality of combined inlet and outlet domes, at the top of said storage and distributed about the same, and a gas supply and return pipe common to all of said connections.
- 75 14. In testimony whereof I hereby affix my signature.

EDMUND E. ALLYNE. 140
